UNITED STATES PATENT OFFICE.

DANIEL HUG, OF DENVER, COLORADO.

BREECH-LOADING FIREARM.

SPECIFICATION forming part of Letters Patent No. 691,056, dated January 14, 1902.

Application filed October 13, 1898. Serial No. 693,381. (No model.)

To all whom it may concern:

Be it known that I, DANIEL HUG, a citizen of the United States, residing at Denver, in the county of Arapahoe, State of Colorado, 5 have invented a new and useful Improvement in Breech-Loading Firearms, which improvement is fully set forth in the following specification and accompanying drawings.

My invention relates to breech-loading firearms of the general construction disclosed in a former patent granted to me; and it consists more especially in improvements in various details therein whereby the construction is simplified and rendered more effective 15 throughout.

The invention consists, first, in an improved construction of pin-bolt, which is provided with a spring fastened there in a novel manner, the head of said spring overlapping a recess in the end of said bolt, whereby it will be impossible for any minute particles, such as grains of sand or similar material, to become interposed between the spring and bolt, so as to render ineffective the operation thereof, said head having an upward extension to prevent unlocking.

The invention also consists in an improved construction of breech-block, which is provided with an overhanging projection to form a housing within, which is located a spring which is adapted to bear upon a suitable portion of the extractor employed.

It also consists in an improved construction of recoil-block, which is adapted to be 35 pivotally mounted upon and work in unison with the breech-block, said recoil-block having a channel and inclined walls and recesses therein adapted to coat with a contiguous portion of the hammer, thereby insuring a 40 positive depression of the hammer to engage with the sear, whereby the hammer is cocked.

It further consists of an improved manner of supporting the extractor-spring located in the breech-block, said spring being supported 45 in a suitable opening and having the housing surrounding the same, said housing serving to protect the spring and to prevent it from vibrating after it has done its work, thereby increasing the durability of said spring.

It also consists of an improved construction of safety-post, its recess, and means for operating said post, whereby novel means are

provided for preventing firing of the gun when not desired.

It also consists of an improved manner of 55 supporting the mainspring and its adjuncts.

It further consists of novel details of construction, all as will be hereinafter fully described, and particularly pointed out in the 60 claims.

Figure 1 is a longitudinal section through the barrel and fore-stock and a side elevation of the parts contained within the frame of a breech-loading firearm, the right-hand side or wall of the frame being removed and the gun being shown in readiness for loading.

Fig. 2 is a similar view showing the position of the parts after firing and showing also in elevation the safety-post, which is carried by the right-hand side or wall of the frame.

Fig. 3 is a longitudinal section with the hammer in elevation, showing the position the parts assume prior to firing. Fig. 4 represents a perspective view of the recoil-block in detached position.

Fig. 5 represents a perspective view of the breech-block in detached position. Fig. 6 represents a perspective view of the extractor in detached position.

Fig. 7 represents a perspective view of the hammer in detached position. Fig. 8 represents a perspective view showing the breech-block, recoil-block, hammer, and extractor in 75 assembled position.

Fig. 9 represents a longitudinal section of a pin-bolt employed. Fig. 10 represents a perspective view of the 80 sear in detached position.

Fig. 11 represents a side elevation of the interior of the right-hand portion of the wall of the frame, showing the safety-post and its adjuncts.

Fig. 12 represents a section on the line *y* *y*, Fig. 11, 85 showing the relative position of the safety-post to the recoil-block and the right-hand wall of the frame and showing also means for actuating said post.

Fig. 13 represents a section on the line *z* *z*, Fig. 11. Fig. 14 represents a section on line *x* *x*, Fig. 2, showing the relative position of the extractor, hammer, and breech-block when assembled.

Similar numerals of reference indicate corresponding parts in the figures.

Referring to the drawings, 1 designates a breech-loading firearm, the same having the trigger-plate 2, upon which is supported the mainspring 3, the latter being secured there-

2
to by means of a screw or other fastening device 4, being supported on the trigger-plate pin 2^X.

5 designates a lug projecting inwardly from the mainspring and having a suitable recess therein, in which the cleaner-rod 6 is adapted to be located, it being noted that said lug 5 is seated in the fore-stock 7.

The free end 8 of the mainspring 3 is provided with a roller 9, which is adapted to contact with a face of the heel 10 of the hammer 11, the latter having the firing-pin 12 formed, preferably, integral therewith, said firing-pin being adapted to work in and protrude through the opening 13 in the breech-block 14, the latter having at its upper rear portion a plurality of ears 15, which fit, respectively, in recesses 16, formed on opposite sides of the forward portion of the recoil-block 17. 18 designates a pin-bolt which passes through openings in the ears of said breech-block and recoil-block, the construction of said pin-bolt being best understood from Fig. 9, in which 19 designates the body 25 of the bolt, the same having the head 20 and the longitudinally-extending recess 21, said recess terminating with the transverse opening 22, in which latter is seated the extremity 24 of the spring 23, which latter terminates 30 in a head 25, which is adapted to be seated in the recess 22^X, it being noted that said head 25 has a lower overlapping portion 27, which covers any space which might exist between the recess 22^X and the longitudinally-extending groove 21, the upper portion 26 of said head 25 being rounded or chamfered, so as to permit the bolt to be readily inserted in position, said portion 26 also preventing disengagement of said pin, it being noted that 35 the outer portion of the ear 15 of the recoil-block 14 has an annular groove or recess 18^X therein, in which the end of said pin 18 and its head 25 terminates.

28 designates a spring which is interposed 45 between the breech-block and the recoil-block at a point below the horizontal line of the ears common thereto.

The lower side of the recoil-block is formed with a longitudinally-extending channel or 50 groove 29, as will be best understood from Figs. 3 and 4, the upper portion of said channel terminating in the curved wall 30, from which extends rearwardly the upwardly-inclined wall 31, which terminates in the recess 32, from which extends the downwardly-inclined wall 33, it being apparent from the foregoing that the function of the recess 32 at the end of the incline 31 is to engage the top end 11^X of the hammer 11, thereby positively insuring the depression of said hammer, so that the latter engages with the end 39 of the sear 40, whereby it is cocked, said sear having the spring 40^X.

34 designates an extractor, the same having an offset upper portion 35, the general location of which in the frame 41 and its function will be understood from Fig. 14.

The lower portion of the extractor has the rearward extension 36 and the curved wall 37, which contacts with an end of the spring 42, which is secured in position within the housing formed by an overhanging projection 43 of the breech-block 14 by means of a pin 44 or other suitable fastening device.

The extractor, hammer, and breech-block 75 are assembled in the frame 41 in the order indicated in Figs. 8 and 14, the same being all mounted upon the sleeve 45, through which passes the pin-bolt 46, the construction of the latter being substantially identical to 80 that of the bolt seen in Fig. 9, although it will of course be apparent that said pins are of different lengths and that the extremity of the pin 46 is seated in the recess 45^X of the outer wall of the frame. The unlocking or 85 disengagement of the pin-bolts 18 and 45 is prevented by reason of the engagement of the deflected portion 26 of the head 25 and of a corresponding spring in the journal-pin 46 with the contiguous portion of the part in 90 which said pin is inserted, as is evident.

The construction and function of the safety-post will now be described, reference being had more especially to Figs. 2, 11, 12, and 13. Figs. 11, 12, and 13 are views of the portion 95 of the right-hand wall of the frame carrying the safety-post, while in Fig. 2 the right-hand wall of the frame is removed, but the safety-post is shown in the position it occupies, the position of the finger-piece for operating the 100 safety-post and the slot in said wall within which it moves being shown in dotted lines, it being understood that the longitudinal section through the frame is taken on a line extending along the inner face of said right-hand wall thereof. The right-hand side 47 of the frame 41 has a recess 48 therein that extends from a point near the upper edge thereof downwardly. The safety-post 49 is situated therein, and the sear 40 extends 110 across the lower end thereof, whereby the lower end of the safety-post can be moved into the path of the sear. The safety-post 49 is fulcrumed at the point 50 and has attached thereto the pin 51, which latter projects 115 through a slot 51^X in the side of said frame, said pin being provided with the finger-piece 52, which is seated in a recess 53 in the outside wall of the frame 41. The position which the safety-post normally occupies is indicated 120 in full lines in Fig. 12, it being seen that said post when seated in its recess is normally out of the path of the recoil-block 17. The top extremity 54 of the safety-post is normally in contact with a curved wall 55 in the upper portion of the recess 48, as will be understood 125 from Figs. 12 and 13, whereby it will be seen that when the pin 51 is actuated in the proper direction, in the present instance backwardly, or in the direction indicated by the arrow a 130 in Fig. 2, the top 54 of the safety-post will be deflected and moved under and into contact with the portion 56 of the recoil-block 17. As a result of the above movement the lower

portion 57 of the safety-post will now be in contact with the portion 58 of the sear, which latter, it will be understood, is seated in the lower end portion of the recess 48, in which 5 the post 49 is placed, whereupon it will be apparent that the sear cannot be moved upwardly by the trigger 59, and consequently the gun cannot be fired and the action cannot be opened, and the cartridge is thus prevented 10 from falling out.

The operation is as follows: The parts after firing appear as seen in Fig. 2, and when it is desired to cock the gun the thumb-piece of the recoil-block 17 is rocked until the latter 15 assumes the position seen dotted in Fig. 2, whereupon it will be evident that the recess 32 will engage the part 11^x of the hammer 11, and the recoil-block, breech-block, hammer, extractor, and their adjuncts can now be rocked 20 into the position seen in Fig. 1. The operator can now insert a cartridge in position, and simultaneously with the insertion of the cartridge the palm of the same hand comes in contact with the thumb-piece of the recoil-block 25 and the latter and the breech-block are moved upwardly into the position seen in Fig. 3. The pulling of the trigger disengages the sear from the hammer and the firing-pin strikes the cartridge, the parts now appearing again 30 as seen in Fig. 2, as is evident. The function of the safety-post 49 is to engage the sear when desired, and so prevent the possibility of the latter moving up and disengaging the hammer, while at the same time the top of 35 said safety-post is moved into the position seen in Fig. 11 and in dotted lines in Figs. 12 and 13, wherefrom it will be seen that the breech cannot be opened, and, if desired, the gun can be suspended in a vertical position 40 upon a finger or fingers by means of the trigger 59 without firing. It will also be noted that the lower end of the extractor-spring having come into contact with the lower end 45 of the extractor on opening the breech thereby starts the shell by leverage, the action of the spring throwing the shell out. It will thus be seen from the foregoing that by the provision of the safety-post constructed as described, the breech-block provided with the 50 spring 42 and the housing therefor, the recoil-block provided with the recess 32, the function of which has been already explained, and the pin-bolts having the headed springs constructed as described I have produced a 55 superior and exceedingly-efficient firearm in which but three movements are necessary—first, a single backward movement of the hand to bring the parts from the position seen in Fig. 2 to the position seen in Fig. 1; next comes the act of inserting the cartridge 60 and bringing the recoil-block into the position seen in Fig. 3, and, third and lastly, pulling the trigger 59, by which the firing is accomplished.

65 It will be evident that slight changes may be made by those skilled in the art which will come within the scope of my invention, and

I do not, therefore, desire to be limited to the exact construction I have herein shown and described.

Having thus described my invention, what I claim as new, and desire to secure by Letters Patent, is—

1. In a breech-loading firearm, the combination of a breech-block, having an overhanging projection 43 forming a housing, a spring 42 secured to said breech-block and within said housing, and an extractor, the latter having a shoulder adapted to contact with the free end of said spring, the latter being disconnected from said extractor.

2. In a breech-loading firearm, the combination of a breech-block provided with a housing, a spring in said housing, an extractor having a shoulder situated in the path of said spring, a recoil-block pivotally mounted upon said breech-block, said recoil-block having a rearwardly and upwardly inclined channel or surface 31, a recess 32 at the upper end of said channel or surface, and a rearwardly and downwardly inclined channel or surface extending from said recess, said recess being adapted to engage the upper extremity 11^x of said hammer.

3. In a breech-loading firearm, the combination with a hammer, extractor, breech-block, recoil-block, of a mainspring 3, a trigger-plate 2 on which said mainspring is mounted, fastening devices 4 common to said trigger-plate and mainspring, a lug 5 projecting inwardly from said mainspring and engaging the fore-stock 7, said lug having an opening through which the cleaner-rod 6 is adapted to pass, and a roller mounted on the free end of said mainspring, said roller bearing upon a suitable portion of said hammer, said mainspring resting normally upon the pin 2^x located in the trigger-plate 2.

4. In a breech-loading firearm, a frame, a recess 48 in the inner wall thereof, a safety-post pivotally mounted in said recess, means for actuating said safety-post from the exterior of the firearm, the upper portion 55 of said recess being rounded or curved, whereby the upper portion 54 of said safety-post is 115 adapted to be deflected into the path of the recoil-block when it is desired to prevent the action from opening.

5. In a breech-loading firearm, the combination with a recoil-block and breech-block, of a pin-bolt, the latter consisting of a suitable body portion having a spring 23 mounted therein, a portion 24 of said spring being deflected and passing transversely through the body of said bolt, a head 25 on said spring, a recess 22^x at the end of said bolt, the inner portion 27 of said head being adapted to seat in said recess to extend across the opening between the said spring and the opposing wall of the recess, and the outer portion 26 of 130 said head being chamfered and projected above said spring, and thus adapted to prevent unlocking or disengagement of said pin and its adjuncts.

6. A pin-bolt consisting of a suitable body portion having a spring 23 mounted therein, a portion 24 of said spring being deflected and passing transversely through the body of said bolt, a head 25 on said spring, and a recess 22^x at the end of said bolt, the inner portion 27 of said head being adapted to seat in said recess, to extend across the opening between the said spring and the opposing wall of the recess and the outer portion 26 of said head being chamfered and projected above said spring, and thus adapted to prevent unlocking or disengagement of said pin and its adjuncts.

7. In a breech-loading firearm, a breech-

block having an overhanging projection 43 forming a housing, a spring 42, secured to said breech-block and within said housing, and an extractor, the latter having a shoulder adapted to contact with the free end of 20 said spring, the latter being disconnected from said extractor, and the lower end of said projection coming in contact with the lower end of said extractor, on opening the breech, thereby starting the shell by leverage, the action of said spring throwing said shell out.

DANIEL HUG.
